UNITED STATES PATENT OFFICE

140,770

DESIGN FOR A VALVE HOUSING FOR WATER SOFTENERS

Eugene P. Jordan, Los Angeles, Calif.

Application January 6, 1945, Serial No. 117,320

Term of patent 14 years

(Cl. D91—1)

To all whom it may concern:

Be it known that I, Eugene P. Jordan, a citizen of the United States and residing at Los Angeles, in the county of Los Angeles, State of California, have invented a new, original, and ornamental Design for a Valve Housing for Water Softeners, of which the following is a specification, reference being had to the accompanying drawing, forming part thereof, in which:

Fig. 1 is a view in elevation of a valve housing

for water softeners as seen from one side thereof showing my new design;

Fig. 2 is a view in side elevation of a valve housing for water softeners as seen from the side opposite that shown in Fig. 1.

I claim:

The ornamental design for a valve housing for water softeners, substantially as shown.

EUGENE P. JORDAN.
